The ornamental design for a slicer, as shown and described.

DESCRIPTION

FIG. 1 is a top plan view of a slicer showing my new design; FIG. 2 is a front elevational view thereof; the rear elevational view being an identical mirror image thereof;

FIG. 3 is a left side elevational view thereof;

FIG. 4 is a cross-sectional view taken along the line IV-IV in FIG. 3;

FIG. 5 is a bottom plan view thereof;

FIG. 6 is a right side elevational view thereof;

FIG. 7 is a front elevational view of the slicer shown in an open position;

FIG. 8 is a front perspective view of the slicer shown in an open position; and,

FIG. 9 is a rear perspective view thereof.

The broken lines shown in the figures represent portions of the slicer that form no part of the claimed design.
